UNITED STATES PATENT OFFICE.

EARL V. HUGHES, OF PERU, INDIANA, ASSIGNOR TO WASMUTH-GOODRICH COMPANY,
A CORPORATION OF INDIANA.

COMBINATION RADIO AND PHONOGRAPH APPARATUS.

Application filed January 11, 1924. Serial No. 685,528.

This invention relates to improvements in combination radio and phonograph apparatus, and the object thereof is to provide a cabinet having twin compartments, in one of which is installed the controller and appendages of a radio receiving set, and in the other compartment a phonographic reproducing means including a megaphone together with a valvular member whereby the megaphone may be selectively utilized in connection with the radio set or the reproducing means accordingly as the valvular member is adjustably positioned. Another object is to so construct and arrange the valvular member as to admit of adjustably varying the volume of sound passing into the megaphone from either the radio set or the reproducing means.

These objects are accomplished by the construction illustrated in the accompanying drawings, in which:

Fig. 1 is a vertical cross section of the apparatus on the line 1—1 of Fig. 3;

Fig. 2 is a plan view of the valvular member; and

Fig. 3 is an elevation of the apparatus in section in a plane at right angles to that of Fig. 1, a portion being broken away.

The characters appearing in the description refer to parts shown in the drawings and designated thereon by corresponding characters.

The invention comprises a cabinet 1 having two compartments 2 and 3 divided by a vertical partition 4, each compartment having a corresponding hinged cover, 5 and 6 respectively, for closing its top. A horizontal platform 7 is positioned in the upper portion of the cabinet and extends within both of the compartments.

A radio controller 8, accessible by raising the lid 5, rests upon the platform within the compartment 2, and a phonographic reproducing means 9, accessible by raising the lid 6, is mounted upon the platform within the compartment 3.

In the lower rear part of the compartment 3 is fixed a base block 10 having a curved opening 11 that extends from the top and extends through the front face of the block where it has communicating connection with the small end of a trumpet 12, the block and trumpet forming a megaphone. The large end of the trumpet opens through the front of the cabinet in the usual manner.

Upon the top of the block 10 is a horizontally movable valvular member 13 having an opening 14 extending vertically therethrough and which affords communication between the tone arm 15 of the reproducing means and the opening 11 of the megaphone when aligned therewith. The top and bottom surfaces of the valvular member are faced with corresponding sheets 16 of felt that have sliding contact respectively with the bottom of the platform 7 and the top of the block 10 so that sounds that may be caused by vibrations of the valvular member are muffled. Except at the opening 14, the top of the valvular member is flat and closes communication between the tone arm and megaphone more or less completely according to the extent the opening 14 is positioned out of alignment therewith, and thus the volume of sound admitted to the megaphone from the reproducing means may be modified.

The valvular member has also a curved opening 17 that extends from one of its ends and through the bottom thereof at a point apart from the vertical opening 14, and on the corresponding end of the member is mounted the "loud speaking unit" 18 of the radio set, which unit has communication through the opening 17 with the megaphone when the said opening 17 is positioned in alignment with the opening 11 in the base block. The unit has electrical connection with the controller by means of a slack cable 19 which admits of movement of the valvular member without disturbing the connection.

An operating bar 20 is fixed on the valvular member 13, one end of which protrudes through the adjacent end of the cabinet, and the other end of which extends through the partition 4 into the compartment 2. A pivoted lever in the compartment 2 has operable connection with the bar 20 at the corresponding end thereof, and the protruding end of the bar is provided with a knob 22 by which the bar is manipulated in moving the valvular member to selectively establish communication between the radio receiving set or the phonographic reproducing means, and the megaphone.

As the valvular member is provided with distinct and separate openings, and the respective connections made therethrough with the radio unit and the reproducing means,

are entirely individual, the openings may be fashioned and of such extent as is found most suitable in each instance.

What I claim is:—

- 5 1. A megaphone appliance for a phonograph including a tone-arm and a radio apparatus including a receiver, comprising a stationary base for said tone-arm; a fixed trumpet member spaced from said base; and 10 a movable valvular member intervening between said base and trumpet member affording support for said receiver and having separate apertures for connecting said tone-arm and trumpet member and said receiver 15 and trumpet member selectively accordingly as said valvular member is positioned.

2. In combination, a radio receiving mechanism, a phonograph mechanism, a sound wave amplifier interchangeably operable with said mechanisms, a block having a through passage and a curved passage entering one side and leaving the bottom thereof, and means for shifting said block in one direction to connect said receiving mechanism with said amplifier through said curved passage and in the opposite direction to connect said phonograph with said amplifier through said through passage.

In testimony whereof I affix my signature.

EARL V. HUGHES.
